(57) **CLAIM**

The ornamental design for a housing for an LED-based lighting apparatus, as shown and described.

DESCRIPTION

FIG. 1 is a top front perspective view of a housing for an LED-based lighting apparatus, showing the new design;

FIG. 2 is a bottom front perspective view thereof;

FIG. 3 is a front view thereof;

FIG. 4 is a bottom view thereof;

FIG. 5 is a top view thereof;

FIG. 6 is a right side view thereof; and,

FIG. 7 is a left side view thereof.
